UNITED STATES PATENT OFFICE.

MATHEW FUNDER, OF FAIRPORT HARBOR, OHIO, ASSIGNOR OF TEN ONE-HUNDREDTHS
TO ROLAND G. SKINNER, OF CLEVELAND, OHIO, AND FORTY-FIVE ONE-HUNDREDTHS
TO FRANK B. CHILSON, OF PAINESVILLE, OHIO.

HATCH-COVER.

1,132,714.

Specification of Letters Patent. Patented Mar. 23, 1915.

Application filed October 3, 1914. Serial No. 864,859.

To all whom it may concern:

Be it known that I, MATHEW FUNDER, a citizen of the United States, residing at Fairport Harbor, in the county of Lake 6 and State of Ohio, have invented certain new and useful Improvements in Hatch-Covers, of which the following is a specification, reference being had to the accompanying drawings.

10 This invention relates to an improved hatch cover and has for its primary object to provide a cover for the hatch openings of vessels which is so constructed that it combines the necessary strength with a 15 water tight closure and ease of operation.

15 In its more specific aspect the invention embodies a plurality of hingedly connected cover sections, and means for causing said sections to assume a folded position upon 20 each other at one end of the hatch opening when the cover is removed.

25 The invention has for another object to provide means movable with the cover for supporting the folded sections thereof in open position.

It is a further object of the invention to provide improved means for easily and quickly securing the cover sections in closed position upon the coaming.

30 The invention has for a further general object to materially improve the construction of hatch covers for vessels so as to produce a water tight closure over the opening, and at the same time admit of the 35 movement of the cover to its open or closed position with facility and despatch.

With the above and other objects in view, 40 the invention consists in novel features of construction, combination, and arrangement of parts as will be hereinafter referred to and more particularly pointed out in the specification and claims.

45 For a full understanding of the invention, reference is to be had to the following description and accompanying drawings, in which—

50 Figure 1 is a plan view, portions being broken away illustrating a hatch cover embodying the present invention in its preferred form; Fig. 2 is a longitudinal section, one-half of the cover being shown in a partly open, folded position in dotted lines; Fig. 3 is an enlarged sectional view 55 of one-half of the cover completely folded;

Figs. 4 and 5 are enlarged detail sectional views illustrating the lap joints between the cover sections, the relative position of the sections when folded being illustrated in dotted lines; Fig. 6 is an enlarged detail section taken on the line 6—6 of Fig. 1; Fig. 7 is a similar section taken on the line 7—7 of Fig. 1; Fig. 8 is an enlarged section taken on the line 8—8 of Fig. 1, showing the means for fastening the two halves of the cover in closed position, and Fig. 9 65 is a similar view showing the detail construction of one of the side fasteners, taken on line 9—9 of Fig. 1.

The hatch openings of vessels carrying coal, ore, grain, or the like, are now generally covered with either wood plank or sectional steel covers, the latter telescoping when drawn out over the opening. The wooden covers require a great deal of labor in putting on or taking the same off, as 75 they are quite heavy, and the telescoping steel covers can not be constructed light enough to enable the same to be handled with facility and still have sufficient strength to withstand the weight to which they are 80 subjected by heavy seas. In both of these cover constructions it is necessary to use tarpaulins as an additional protecting cover to prevent the sea water or even rain from entering beneath the wood or steel cover and 85 entering the hatch opening. The steel or wooden covers must also be securely clamped upon the coaming of the hatch opening at frequent intervals.

It is the primary purpose of my invention 90 to provide at a moderate expense a cover having the requisite strength, but which may also be easily moved to its open or closed position, and which will be absolutely water tight when disposed over the 95 hatch opening without necessitating the use of tarpaulins.

In attaining the above end, the hatch cover consists of two primary parts, each of which includes relatively wide and narrow 100 sections designated by the numerals 5 and 6, respectively. These cover sections are constructed of metal plates, and as shown the wide and narrow sections are alternately arranged. The sections of the cover are 105 equipped at spaced points along each of their longitudinal edges with hinge castings 7, the castings contiguous to one edge of the

plate being arranged upon the opposite side of the plate with respect to the other series of castings. Each of the metal cover sections 5 and 6 is further provided upon its 5 upper side and at one of its longitudinal edges with spaced angle bars, 8 and 9, respectively, which extend the entire length of the cover sections. One flange of each of said bars is securely riveted to the cover 10 section, while the other flange projects at right angles to the body of the cover section. The flange of the angle bar 8 is disposed beyond the longitudinal edge of the plate while the corresponding flange of the inner 15 angle bar 9 is of slightly greater width than the flange of the bar 8. The purpose of these angle bars will be hereinafter particularly referred to. To the other longitudinal edge of each of the cover sections a 20 bar 10 of Z-shaped form in cross section is riveted. The intermediate portion of this bar extends in a plane at right angles to the cover section and the laterally disposed flange 11 of said bar extends in parallel relation to the cover section and beyond its 25 longitudinal edge, as clearly shown in Figs. 4 and 5 of the drawings. To this latter flange a plate 12 is riveted, said plate having an angle bar 13 fixed to one face thereof. 30 This bar is opposed to the Z-shaped bar 10 and its unattached flange extends in parallel relation to the intermediate portion of said bar 10 and is spaced from the edge of the plate 12, thereby producing a longitudinally extending stop shoulder 14. The 35 hinge castings 7 on one edge of the wider cover sections 5 are secured upon the plate 12. The castings 7 of the contiguous cover sections are, of course, connected by the 40 hinge pivots 15.

It will be seen from Fig. 2 of the drawings that when the cover sections are arranged in closed position upon the coaming of the hatch opening, the hinge pivots are 45 alternately disposed above and below the plane of the body plates constituting the several sections of the cover.

The deck of the vessel slopes or curves in the usual manner and to said deck around 50 the edges of the hatch opening, the coaming 16 is secured. This coaming is of shallow channel-shaped form in cross section, the flanges on the longitudinal edges thereof projecting outwardly. The lower or base 55 flange of the coaming wall is fastened to the deck, while upon the upper flange thereof the several sections of the hatch cover rest when in their closed positions. To the outer face of the coaming wall an angle bar 17 is 60 secured, said bar being located immediately beneath the upper flange on said wall and having its wider horizontally disposed flange 18 projecting outwardly beyond the edge of the flange on the coaming wall. 65 The end edges of each of the cover sections

and also the longitudinal edge of the end section of each half of the cover which rests upon the end wall of the coaming are downwardly bent or curved, as shown at 19, to rest upon the outwardly extending flange 18 70 of the angle bar 17 when the cover is closed. It is to be noted that the plates 12' which are carried by each of the wider cover sections 5 are of greater length than said cover sections and extend beyond the opposite end 75 edges thereof, while the remaining plates 12 carried by the narrower cover sections 6 are of substantially the same length as the cover sections. To each of these latter cover sections at opposite ends of the plate 12, 80 a curved casting 20 is secured, and to the under side of each of said plates carried by the wider sections of the cover a casting 21 is secured, said latter castings being provided in their bottom faces with recesses or 85 notches 22.

The parts above described constitute the cover proper and before proceeding with a detail description of the means for manipulating the two halves of the cover in order 90 to move the sections to their open positions or to their closed positions, I will first explain the purpose of the particular hatch cover construction above set forth.

One important object of the angle bars, 95 Z bars, and plates 12 is to reinforce or stiffen each of the section plates 5 and 6 to enable the same to withstand the weight of the immense quantities of water which will be thrown thereon in a heavy sea. It is to be 100 particularly noted that these bars are each arranged on the top of the cover plates so that they will extend over the coaming walls. They will thus have the necessary support at opposite ends, which could not 105 be provided if said plates were arranged on the under side of the cover sections. The peculiar arrangement of these bars also results in another marked advantage in the practical operation of the hatch cover. Referring to Figs. 4 and 5 of the drawings, it 110 will be noted that the only place where water may leak through between the plate sections is between the angle bars 9 and 13.

Any water, however, entering at this point 115 will run into the rectangular channel formed at the joint between the cover sections by the angle bars 8 and 9, and it will be noted that in view of the arrangement of these bars, no water can enter the hold of 120 the vessel until said channel is completely filled so that the water would flow over the edge of the angle bar 8 between the same and the Z bar 10. Referring now to Figs. 6 and 7 of the drawings, it will be observed 125 that the castings 20, 21 close the ends of the channels so that water can not enter the same. The inner faces of these castings are formed with cavities 20' and 21' respectively which afford communication between 130

the channels and the holes or openings 19' formed in the downwardly turned ends of the cover plates. It is thus apparent that the water which may enter the channel will 5 drain or escape therefrom into the space between the horizontal flange 18 of the angle bar 17 and the outwardly projecting flange on the upper edge of the coaming wall from whence it will find its escape beneath the 10 bent down edges of the plates 5 and 6. It is therefore manifest that no water can possibly leak through the joints between the several cover plates and enter the hold of the vessel. When heavy seas wash over the 15 cover, some water will probably find its way into these channels, but in view of the fact that the seas would only cover the deck of the vessel for a short time, the channel would have ample time to discharge any 20 water collecting therein between the seas. It is to be borne in mind, however, that I do not desire to limit myself to the details of the channel construction and protecting means for the cover sections, shown in the 25 accompanying drawings, but also claim as a part of my invention any mechanical structure whereby the desired protection and drainage may be afforded. The flange 18 on the angle bar 17 also has an additional 30 function, in that it protects the turned down ends 19 of the cover plates from the immense water pressure of heavy seas which might otherwise tend to tear the cover off of the coaming wall.

35 The construction and arrangement of the several parts which I shall now describe are identical at each end of the hatch opening.

The section 5 of the cover, which is disposed over the end of the hatch opening, is 40 provided adjacent its opposite ends with spaced arms 23 which project over the flanged edge 19 of said cover section. Between each of these pairs of arms the bars 24 are fulcrumed as at 25, said fulcrum 45 being located at a bend in the bar which connects the long and short arms 26 and 27, respectively. The longer arm of said bar when the cover is closed rests upon the inner angle bar 9 carried by the cover section. 50 The other end of each of these bars 24 is pivotally mounted in a block or casting 29 which is permanently fixed to the deck of the vessel. At opposite ends of the end section of the cover the rails 30 are 55 arranged, said rails having straight parallel portions adapted to be disposed through openings in outwardly projecting ears 31 which are fixed upon the coaming wall 16. The extremities of the rails are adapted to 60 be seated in openings provided in the deck castings indicated at 32. However, if desired, these rails may be permanently mounted. Each of said rails is formed with a gently curved section 33 which is disposed 65 above the plane of the cover sections when

the latter are closed, and faces inwardly toward the center of the cover. This curved portion 33 of the rail merges into a substantially semi-circular upper portion 34. At this point attention may be directed to 70 the fact that the notches 22 in the castings 21 on the ends of the longer plates 12' are disposed in line with the rails 30 while the castings 20 are inside of said rails.

To the inner end section of each half of 75 the cover and on opposite sides of the center thereof spaced plates 35 are fixed at one of their ends, said plates extending in relatively opposite angular directions and riveted to the cover. The free edge of one of 80 these end sections has a longitudinally extending Z-shaped bar 36 secured thereto in spaced relation to its extreme edge and to the unattached horizontal flange of this bar a plate 37 is fixed. An angle bar 38 is also 85 secured to the edge of this cover section in spaced relation to the bar 36 and the edge of the plate 37 is outwardly bent away from the edge of the outwardly extending flange of the bar 38, as indicated at 39. Between 90 this bent edge of the plate 37 and the flange of the bar 38 the outwardly projecting horizontal flange 40 of a Z-shaped bar secured upon the free longitudinal edge of the opposed end section of the other half of the 95 cover is adapted to engage.

The halves of the hatch cover are securely held together at their abutting ends by means of fasteners, shown in detail in Fig. 8 of the drawings. Three of these fasteners are preferably employed, although it will be understood that a greater or less number may be used if desired. Each of said fasteners includes an arm 45 which is pivotally mounted at one of its ends between spaced ears 46 secured upon the Z-shaped bar 36 on one cover section. The other end of this arm is bent or curved as at 47 and upon the extremity thereof a locking bar 48 is pivoted adjacent one of its ends. In 100 the end of the bar 48 which is pivotally connected to the arm 45 an adjusting bolt 50 is threaded. One end of this bolt is adapted to be received in a suitable seat provided for the same upon the intermediate portion of the Z-shaped bar 40 and it will be obvious that as soon as the bar 48 has been swung into position the pressure exerted upon the bar 48 above its pivot will tend to force the other end 49 of said bar downwardly into 105 binding engagement upon the cover.

As an additional means of security and to hold the cover sections in tight engagement upon the coaming wall, I employ side and end fasteners such as that illustrated in Fig. 9 of the drawings. These fasteners are arranged upon the opposite side walls of the coaming, preferably one for each of the cover sections, and upon the end walls of the coaming two such fasteners are mounted for 110 115 120 125 130

engagement upon the end sections of the cover. Each of these fasteners includes a curved arm 51 which is pivoted at one end upon a block or casting 52 secured upon the 5 coaming wall. When in its locked position the arm 51 extends upwardly and inwardly over the cover section, and upon the other end thereof a bar 53 is fulcrumed as at 54. This bar is provided with an angular end 10 portion 55 in which an adjusting bolt 56 is threaded. The operation of this device is substantially identical with the fastener shown in Fig. 8, the outer end of the bolt 56 being received in a cupped seat provided 15 upon a plate secured to the cover section.

For the purpose of facilitating the movement of the several sections of each half of the cover to their open positions, I employ a tripod 41 which is adapted to be arranged 20 adjacent one end of the hatch cover and suitably anchored temporarily to the deck. A sheave or pulley 42 is mounted upon the upper end of the tripod and around the same the cable 43 extends. One end of this cable 25 is branched as at 44 and connected to the corresponding plates 35 upon opposite sides of the center of the hatch cover sections, said branch cables being provided with suitable hooks for engagement with the openings 30 in said plates. The other end of this cable may be attached in any suitable manner to a drum operated by an engine.

Having now described the several structural features of my invention, its operation 35 will be understood as follows: Assuming that both parts of the cover are in closed position upon the coaming wall 16, the several fastening devices are first loosened and disengaged from the cover sections, and the fasteners which connect the opposed ends of the 40 two halves of the cover are also removed from their locked positions. The tripod 41 is now placed in position and the cable passed around the pulley 42 and connected 45 to the inner end section of one-half of the cover, as above explained. When the engine is operated and the cable wound upon its drum, the pull exerted by said cable slides the cover sections longitudinally upon the 50 upper flanges of the coaming. This sliding movement of the cover sections causes the bars 24 to be forced upwardly and backwardly upon the deck blocks 29. The castings 21 on the first of the cover sections 55 soon engage the inclined sections 33 on the side rails 30 and sliding along same break the joint between said cover section and the next narrower section 6 of the cover. As the movement of the cover is continued along 60 the upper edge of the coaming wall, and the castings 21 continue their movement over the upper curved portions 34 of the rails, the arms 27 of the bars 24 will rest upon the deck. The first cover section at this time 65 must leave the rails 30, as it is pushed by the

succeeding sections of the cover whereby said first section is caused to swing backwardly against the angularly extending long arms 26 of the bars 24. The joint between the sections having been broken by the engagement of the castings 21 upon the rails 30, the next section of the cover will fold upon said first section. However, before the second section moves into parallel relation to the first section which is disposed upon the 70 bars 24, the succeeding third section of the cover which is relatively narrow will engage upon the upper portions of the rails 30, the castings 21 moving upon and being supported by said rails. By the time the second 75 section arrives at its completely folded position, the following section will be disposed at such an angle with respect to the next succeeding section of the cover that it will swing upwardly and backwardly upon said second 80 section, as it is forced or pushed to its closed position. It will thus be seen that the several plates or sections of each half of the cover are compactly folded and supported upon the bars 24 so that they occupy comparatively 85 little space. The lower edges of the folded sections rest upon the inclined brace bars 26'. After one half of the cover has been thus folded in its open position, the tripod 41 is moved to a position beyond the 90 opposite end of the hatch opening and the other half of said cover opened in the same manner. The halves of the cover may be as readily moved to their closed positions over the hatchway by arranging the cable supporting tripod at the far end of the hatch opening and connecting the cable to the other pair of plates 35 which extend toward the free edge of the cover sections. The sections 95 will readily move from their folded positions to their closed positions upon the coaming wall, the castings 21 engaging upon the rails 30 which serve to direct the sections of the cover upon the coaming as they are unfolded. The two halves of the cover are then 100 securely fastened upon the coaming wall in the manner above described.

It will be noted that the bars 24 have a twofold object, namely, first, to carry the end section to a position beyond the hatch opening, and secondly, to provide a seat or support for the folded cover sections. This position of the folded sections will permit a loading chute to be placed close to the end 110 of the hatch opening without interfering with the cover and will still leave sufficient walking space between the cover and the deck rail of the vessel.

From the foregoing description, taken in connection with the accompanying drawings, the construction, manner of operation and several advantages of my invention will be clearly and fully understood. It will be obvious that by constructing the two halves 125 of the cover in a plurality of foldable sec- 130

- tions, the cover may be very easily and quickly moved from its closed to its open position or vice versa and with a minimum of manual labor. As above stated, the rails 5 30 are preferably removably mounted in position for use so that they can be carried together with the tripod from one hatch to the other. In view of the very simple form and construction of the several parts employed it will further be obvious that the 10 device can be produced at small manufacturing cost.
- While I have shown and described the preferred construction and arrangement of 15 the several elements, it will be understood that the invention is susceptible of considerable modification in the details and proportions thereof, and I therefore reserve the privilege of resorting to all such legitimate 20 changes as may be fairly embodied within the spirit and scope of the invention as claimed.
- I claim:
1. A hatch cover, means for moving said 25 cover to open or closed position over the hatch opening, and a support moved by the cover to its supporting position to receive and support the cover in open position.
2. A hatch cover, means for moving said 30 cover to open or closed position over the hatch opening, and a support connected to the cover and moved thereby into position upon the deck of the vessel to receive and support the cover in open position.
3. A hatch cover including a plurality of 35 foldable cover sections, means for moving said sections and disposing the same in superposed relation entirely beyond the coaming wall and out of contact therewith, and a support connected to one of the cover 40 sections and movable to its supporting position when said cover is opened to receive and support the cover sections.
4. A hatch cover including a plurality of 45 foldable cover sections, means for moving said sections longitudinally with respect to the hatch opening and folding the same upon each other in open position at one end of said hatch opening, and means connected 50 to one of said sections and movable therewith to support the folded sections in their open position.
5. A hatch cover, means for moving said 55 cover to open or closed position over the hatch opening, and a support pivotally mounted upon the vessel deck and moved by the cover to its supporting position to receive and support said cover in open position.
6. A hatch cover including a plurality of 60 foldable cover sections, means for moving said cover sections in superposed relation to each other entirely beyond the coaming wall and out of contact therewith, and a 65 support mounted upon the vessel deck and moved by one of the cover sections as said cover sections are folded upon each other to dispose the support in position to receive the superposed cover sections.
7. A hatch cover, means for moving said 70 cover to open or closed position over the hatch opening, and a support permanently and movably mounted upon the vessel deck and moved by the cover into position to receive and support said cover in open position.
8. A hatch cover including a plurality of 75 hingedly connected sections, adjacent sections being foldable in opposite directions upon each other, means for moving said sections longitudinally over the hatch opening, and means arranged at one end of the hatch opening to break the hinge joints between 80 said sections and cause the same to fold.
9. A hatch cover including a plurality of 85 hingedly connected sections, adjacent sections folding in opposite directions upon each other, means for moving said sections longitudinally over the hatch opening, means arranged at the end of the hatch 90 opening to break the hinge joints between said sections and cause the same to fold, and bars pivotally mounted at one of their ends adjacent to the hatch opening and connected to one of the cover sections for movement 95 therewith, said bars each having an arm adapted to receive and support the sections of the cover in their folded position.
10. A hatch cover including a plurality of 100 hingedly connected sections, adjacent sections folding in opposite directions upon each other, means for moving said sections longitudinally over the hatch opening, means arranged at one end of the hatch opening to break the hinge joints between 105 said sections and cause the same to fold, and bars pivotally mounted at one of their ends adjacent to the hatch opening provided with angularly disposed arms extending over and upon one end section of the cover, said bars being pivotally connected to said end section and movable therewith when the sections are folded to dispose said arms in an upwardly inclined position and provide a support for the folded cover sections.
11. A hatch cover including a plurality of 110 hingedly connected sections, rails arranged at opposite sides of the hatch opening and at one end thereof, means for moving the cover sections longitudinally over the hatch 120 opening, means carried by alternate cover sections for engagement upon said rails whereby the hinge joints are broken and the sections caused to fold upon each other, and means to receive and support the folded sections at the end of the hatch opening.
12. A hatch cover including a plurality of 125 hingedly connected sections, adjacent sections being adapted to fold in opposite directions upon each other, means arranged at 130

the end of the hatch opening to coöperate with means on the cover sections and break the hinge joints in the sliding movement of the cover in one direction whereby the sections are caused to fold upon each other, means at one end of the hatch opening to receive and support the folded cover sections, and means adapted to be connected to one of the sections to move the same to their open or closed positions.

13. A hatch cover including a plurality of hingedly connected sections, curved rails removably mounted at opposite sides of the hatch opening and at one end thereof, means on the cover sections to coöperate with said rails and break the hinge joints between the sections whereby the same are caused to fold upon each other, means for moving said sections over the hatch opening to their open or closed position, and means connected to one of the sections and movable therewith to support the cover sections in their folded position.

14. A hatch cover consisting of two halves, each including a plurality of hingedly connected sections, means for sliding the halves of the cover longitudinally over the hatch opening, relatively stationary means to cause the cover sections of each half to fold upon each other as they are moved to their open positions, means for fastening the contiguous sections of the two halves of the cover together when the same are in closed position, and additional means for fastening each cover section to the hatch coaming.

15. A hatch cover, means for moving said cover to open or closed position over the hatch opening, and a support movably mounted upon the vessel deck and pivotally connected to said cover to be moved thereby to its supporting position to receive and support the cover in open position.

16. A hatch cover including a plurality of foldable cover sections, means for moving said sections longitudinally with respect to the hatch opening, and means arranged at the end of the hatch opening to break the joints connecting said sections.

17. A hatch cover, means for moving said cover to open or closed position over the hatch opening, and a support movably mounted upon the vessel deck and pivotally connected to said cover and moved by the cover into position to receive and support the cover in an open position entirely out of contact with the coaming wall.

18. A hatch cover including a plurality of foldable cover sections, and reinforcing means arranged upon the upper side of each cover section and adapted to co-engage with the reinforcing means on the adjacent section to provide a series of transverse reinforcements at the joints of the cover.

19. A hatch cover including a plurality of

foldable cover sections, and a transversely extending water drain arranged at each joint of the cover upon the upper side thereof substantially as and for the purpose set forth.

20. A hatch cover including a plurality of foldable cover sections, and protected water drains extending transversely across the upper side of the cover at each joint thereof substantially as and for the purpose set forth.

21. A hatch cover including a plurality of foldable cover sections, and protected drains extending transversely upon the upper side of the cover at each joint thereof and extending at their ends over the coaming wall of the hatch opening substantially as and for the purpose set forth.

22. A hatch cover comprising a series of hingedly connected foldable sections, and drainage means at each joint of the cover to exclude water from the hatchway.

23. A hatch cover including a series of hingedly connected foldable sections, and sectional drainage channels arranged upon the upper surface of the cover at each joint thereof and arranged upon said cover sections to permit the same to be folded to their open positions.

24. A hatch cover including a series of hingedly connected foldable sections, water arresting means at each joint of the cover, and drainage channels to receive the seepage through said arresting means.

25. A hatch cover including a plurality of foldable cover sections, means for moving said sections to an open position and in folded superposed relation to each other, and a support connected to one of said sections and moved thereby to its supporting position to receive and support the cover sections out of contact with the coaming wall.

26. A hatch cover including a plurality of foldable cover sections, means for moving said sections to an open position and in folded superposed relation to each other, and a support engaged by one of the cover sections and moved thereby to its supporting position to receive and support the sections in a vertically inclined plane with respect to the coaming wall.

27. A hatch cover including a plurality of foldable cover sections, means for moving said sections to an open position and in folded superposed relation to each other, and a support engaged by one of the cover sections and moved thereby to its supporting position to receive and support the sections in a vertically inclined plane with respect to the coaming wall and entirely out of contact therewith.

28. A hatch cover including a plurality of foldable cover sections, means for moving said sections to an open position and in folded superposed relation to each other,

- and a support movably mounted upon the vessel deck and permanently connected to one of the cover sections to be moved thereby to its supporting position to receive and support said sections. 5
29. A hatch cover including a plurality of foldable cover sections, means for moving said sections to an open position and in folded superposed relation to each other, and 10 a support movably mounted upon the vessel deck and permanently connected to one of the cover sections to be moved thereby to its supporting position to receive and support said sections in a vertically inclined position 15 with respect to the coaming wall and entirely out of contact therewith. 20
30. A hatch cover including a plurality of foldable cover sections, means for moving said sections to an open position and in folded superposed relation to each other, and a support pivotally mounted upon the vessel deck and permanently connected to one of the cover sections to be moved thereby to its supporting position to receive and support 25 the folded cover sections in open position. 30
31. A hatch cover including a plurality of foldable cover sections, means for moving said sections to an open position and in folded superposed relation to each other, and a support movable with the cover to its supporting position when the cover sections are folded upon each other to receive and support said cover sections in an outwardly inclined position entirely beyond the coaming wall. 35
32. A hatch cover including a plurality of foldable cover sections, means for moving said sections to an open position and in
- folded superposed relation to each other, and 40 a pair of supporting members pivotally mounted upon the vessel deck to be engaged by one of the cover sections and moved thereby to their supporting positions to receive and support the folded cover sections 45 in an outwardly inclined position with respect to the coaming wall. 33. A hatch cover comprising a series of relatively movable cover sections, and drainage means carried by each cover section to 50 extend over the joints between the several sections when the cover is closed and exclude water from the hatchway. 34. A hatch cover comprising a series of relatively movable cover sections permanently connected together at their contiguous edges, and a drainage channel carried by each of the cover sections to extend over the joint between said sections when the cover is closed and exclude water from the hatch- 55 way. 35. A hatch cover comprising a series of cover sections hingedly connected together at their contiguous edges to fold upon each other, a water receiving channel secured upon each section to extend over the hinge joint between the same and the contiguous section, and water arresting means carried by the latter cover section and engaged with said channel when the cover is closed 60 to exclude water therefrom. 65
- In testimony whereof I hereunto affix my signature in the presence of two witnesses.
- MATHEW FUNDER.
